GENERATOR ATTACHMENT FOR TRACTORS

Noel H. Montgomery, Unionville, Mo.

Application January 25, 1945, Serial No. 574,545

3 Claims. (Cl. 74—11)

1

This invention relates to a generator attachment for tractors. Many of the standard tractors are not provided with electric generating equipment, and in some cases there are no projecting shafts or pulleys which can be effectually utilized for driving a generator.

The principal object of this invention is to provide a neat, simple, and highly efficient attachment which can be applied to a standard tractor, more particularly of the "Caterpillar" type, and which will support a standard automotive generator and transmit power thereto from the engine of the tractor.

Another object of the invention is to so construct the attachment that it can be quickly and easily applied to the tractor engine without requiring any changes therein or machine work thereon, and which will not interfere in any way with the normal operation of the engine.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a side view of the improved attachment, partially in section, illustrating in broken line the relative position on the co-acting portions of a tractor engine;

Fig. 2 is a plan view of the improved attachment; and

Fig. 3 is a front view thereof.

The invention could be used on many types of tractors. It is more particularly designed for a "Caterpillar" tractor. On such tractors the fan and water pump shaft are the only shafts that are open to the outside of the engine. These shafts, however, rotate in the wrong direction, are inconvenient for use in driving a generator, and are in such positions that no available space is allowed for the generator. The shaft of the water pump of the tractor, however, although entirely enclosed, rotates in the proper direction and is in the proper position for this use. The shaft is provided with a drive gear which is accessible by removing a cover plate. This improved attachment is designed to replace the said cover plate and to make use of the drive gear for power purposes.

In the drawing, the water pump is indicated 55

2

in broken line at 10, the water pump shaft at 11, the water pump drive gear at 12, and the water pump drive housing at 13.

The improved attachment is designed for mounting on the water pump gear housing 13 of the engine of the tractor. To apply this attachment thereto, the standard cover plate is removed and a gear case 14 is secured in place of the cover plate. The case is provided with a base flange 15 which overlaps the frame of the opening in the gear box housing 13, and is secured thereto by means of suitable cap screws 16, which may be the screws that formerly held the cover plate in place thereon.

15 The gear case 14 is provided with bearings 17 in its opposite faces, in which a gear shaft 18 is journaled. A drive gear 19 is keyed or otherwise secured on the shaft 18 within the case 14. This gear is of the proper diameter, type, and 20 shape to mesh with the pump gear 12 when the case 14 is secured in place on the housing 13. The shaft 18 terminates on the exterior of the gear case 14 in a V-belt pulley 20.

A U-shaped generator bracket 21 is formed on 25 the case 14. The two arms of the bracket 21 are drilled to receive hinge bolts 22, by means of which a standard automotive electrical generator 23 is hingedly mounted. The generator is provided with end plates 24, both of which are 30 provided with an ear 25 which are mounted on the hinge bolts 22. The front end plate 24 is provided with a second ear 26 terminating in a clamp bolt 27 having a clamping nut 28. The clamp bolt 27 rides in a longitudinal slot 29 in a 35 hinged brace member 30, and can be clamped in any desired position along the slot 29 by means of the nut 28. The brace member 30 is mounted on a hinge bolt 31 extending through a projecting lug 32 on the gear case 14.

40 The generator 23 is provided with the usual generator shaft 33 upon which a second V-belt sheave 34 is mounted. An endless V-belt 35 is trained around the V-belt sheaves 20 and 34. The V-belt can be adjusted by varying the position 45 of the clamp bolt 27 in the slot 29 to obtain the desired tension therein.

To install the device it is only necessary to remove the cover plate from the pump housing 13 and set the base flange 15 thereon. The cap screws are then tightened and the device is ready for operation.

It can be readily seen that as the gear 12 rotates to drive the pump 10, it will also drive the gear 19 and, through the medium of the belt 35, the generator 23.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A combined power takeoff device and generator support for internal combustion engines comprising: a gear shaft; a driven gear mounted on said shaft; a gear housing about said gear; bearings in the opposite sides of said housing supporting said shaft, the lower portion of said housing being open below said bearings to allow said gear to project downwardly therefrom; an attachment means on said housing at each side of the open portion thereof; a belt drive sheave mounted on said shaft exteriorly of said housing; a generator-supporting bracket mounted on said housing; and an endless belt extending from said drive sheave to driving engagement with the generator.

2. A combined power takeoff device and generator support for internal combustion engines comprising: a gear shaft; a driven gear mounted on said shaft; a gear housing about said gear; bearings in the opposite sides of said housing supporting said shaft, the lower portion of said housing being open below said bearings to allow said gear to project downwardly therefrom; an attachment means on said housing at each side of the open portion thereof; a belt drive sheave mounted on said shaft exteriorly of said housing; a U-shaped generator bracket secured to and extending parallel to said shaft; means for pivotally mounting one side of a generator at each extremity of said bracket; a brace member hinged to said housing; means for adjustably securing said brace member to the other side of said

generator; and an endless belt transmitting power from said belt drive sheave to the generator.

3. A power takeoff device comprising: a gear shaft; a gear mounted on said shaft; a housing enclosing the upper portion of said gear and terminating below the center-line thereof so as to leave the lower portion of said gear exposed; bearings in the opposite sides of said housing rotatably supporting said shaft; attachment means formed upon said housing about its lower open side; a belt sheave mounted on said shaft at one side of said housing; a U-shaped supporting bracket fixedly mounted on said housing; a brace member hinged to said housing alongside said supporting bracket; and an endless V-belt transmitting power from said belt sheave to the generator.
